UNITED STATES PATENT OFFICE

MAX SELLINGER AND PHILIP RAWDIN, OF BROOKLYN, NEW YORK

TELEPHONE-RECEIVER SUPPORT

Application filed April 5, 1928. Serial No. 267,747.

This invention relates to a telephone of a well known type, consisting of a standard carrying a receiver and means to support a transmitter attached by a flexible cord in a 5 manner to control the switch.

Such instruments are subject to several disadvantages; frequently both hands are required to manipulate the instrument and always one hand is used to support the receiver when off its hook, rendering it difficult to make notes generally necessary.

It is also fatiguing to be obliged to support the receiver, fifteen ounces in weight, for any considerable period of time, as during numerous lengthy conversations, with the arm raised to an awkward and tiresome angle.

It is therefore one of the objects of the present invention to provide a receiver, preferably of the watch case type, with means for 20 automatic support during its period of use and in proper position relative to the transmitter, whereby, if the instrument is on a suitable support, both hands are free.

A further feature is in the provision of 25 means whereby the receiver may be adjusted to suit the user, when in an operative position and to control the switch when in another position, as is now done in standard instruments.

Another aim is to produce an improved 30 receiver support suited for use in connection with coin box control instruments.

These several important features are attained by the novel construction, combination 35 and arrangement of parts as hereinafter described and shown in the accompanying drawings, forming a material part of this disclosure, and in which:—

Fig. 1, is a side elevational view of a conventional type of telephone instrument showing 40 an application of the invention as disposed in its rest or inactive position.

Fig. 2, is a similar view of the same but 45 illustrating the device in an operative position.

Fig. 3, is a front elevational view of the device as it appears in Fig. 1.

Fig. 4, is a side elevational view showing 50 the device as applied to a coin controlled telephone instrument.

As shown in Figs. 1 to 3 the device will be seen to consist of an attachment applicable to the usual type of telephones consisting of a base 10 and a standard 11 surmounted by a forked bracket 12 in which is pivoted a transmitter 13 having a forwardly extending mouthpiece.

Reaching outwardly through a slot in the standard 11, is a lever 14 ordinarily terminating in a hook adapted to support a receiver, the weight of which maintains the hook in a downward position whereby a switch, controlling current to the transmitter, is held in an open position, the current being conducted to the instrument by a cord 15 entering the base.

In the improved device a clamp 17 is adjustably engaged on the standard 11 to support a forked bracket 18 in which is pivoted, at 19, a hollow lever 20 having an opening 21 70 to receive the cord 16, the lever being shaped to act as a guard for the cord, the outer end of which is branched to deliver current to the receiver 22.

In the preferred form of this device a receiver of the watch case type is shown, but obviously the shape of the receiver is immaterial, the same being held by a clamp ring 23 carried at the outer end of a bar 24 slidably adjustable in the hollow lever 20 and 75 tightened when adjusted by the set screw 20'.

The lever 20 is shaped near its pivot to contact with the switch lever 14 when the instrument is not in use, as best seen in Fig. 1, but may be swung into an operative listening 85 position, as seen in Fig. 2, when it is desired to use the same, and it will be understood that when the lever 20 is swung forward, it will be clear of the switch lever, permitting it to 90 rise and close the telephone circuit.

In order to maintain the receiver 22 in a position convenient for use, the lever 20 is provided with an arm 25 below its pivotal point, this arm making contact with a stop 95 26 outstanding from the clamp 17.

From the foregoing it will be seen that the receiver may be adjusted with respect to the ear of a person speaking into the transmitter, and that both hands are free to make mem- 100

oranda as desired, while the hands and arms are relieved from holding the receiver.

In the modified form shown in Fig. 4, a box type of instrument is designated by the 5 numeral 30 having a coin receiving entrance 31 and a forked, forwardly extending bracket 32 pivotally supporting a transmitter 33.

A bracket 34 carries a pivot 35 on which is mounted a lever 36 operable with respect 10 to the switch lever 37 and suited to receive a slideable bar 38 to which is pivotally connected a clamp ring 39 engaging the receiver 40.

At the end of the lever 36 is a projection 15 41 adapted to engage a stop 42 formed on the bracket 34, all these several elements being substantially as previously described.

From the foregoing it will be seen that a simple but efficient device for the purposes 20 set forth has been disclosed in the preferred forms of their embodiment; but it is not desired to restrict the details to the exact construction shown, it being obvious that changes may be made without exercising invention or conflicting with the scope of the 25 appended claims.

Having thus described the invention what is claimed as new and sought to secure by Letters Patent, is:—

30. 1. The combination with a telephone instrument stand having a transmitter and a lever pivoted in said stand to control current to the transmitter, of a bracket adjustable on said stand, an offset arm pivoted in the bracket to swing rearward and engage the control lever when the telephone is not in use, a receiver carried by the arm, and a stop integral with said arm engageable by said bracket when the receiver is in a forward operative position, a longitudinal groove in said arm to receive and protect the wire cable from the receiver and a recess in said arm below said grooved portion through which the wire cable may be threaded.

45. 2. The combination with a telephone instrument stand, of a bracket adapted to be associated with the instrument, an offset receiver-carrying arm pivoted on the lower end thereof to said bracket, said offset portion being adapted to overlie and depress the receiver hook of the instrument to break the circuit when not in use and to be swung forwardly to release the receiver hook when in operative position, said arm having a longitudinal depression adapted to receive and protect the electric cable from the receiver, a bar slidably engaged with said arm, means for clamping said bar in various positions of adjustment, a receiver adjustably carried 50 by said arm, and a recess in said arm near its pivot, through which the electric cable may pass.

60. 3. The combination with a telephone instrument stand, of a bracket adapted to be 65 associated with the instrument, an offset re-

ceiver-carrying arm pivoted on the lower end thereof to said bracket, said offset portion being adapted to overlie and depress the receiver hook of the instrument to break the circuit when not in use and to be swung forwardly to release the receiver hook when in operative position, said arm having a longitudinal depression adapted to receive and protect the electric cable from the receiver, a cap adapted to cover said depression and cable, a bar slidably engaged between the arm and said cap, means for clamping said bar in various positions of adjustment, a receiver adjustably carried by said arm, and a recess in said arm near its pivot, through which the electric cable may pass.

Signed in the city, county and State of New York, this 7th day of March, 1928.

MAX SELLINGER.
PHILIP RAWDIN.
